CHARLES W. BREED, OF WESTERN SPRINGS, ILLINOIS.

SPLICE BAR.

Application filed February 2, 1928. Serial No. 251,254.

My invention relates generally to rail joints and more particularly to splice bars used in rail joints and to the shaping and proportioning of such bars to obtain the maximum efficiency.

It is an object of my invention to provide a splice bar having such distribution of metal that the stresses in the outermost fibres above the horizontal neutral axis substantially equal the stresses in the outermost fibres below said axis, and also that the stresses in the outermost fibres to the right of the vertical neutral axis substantially equal the stresses in the outermost fibres to the left of said axis, and to obtain this distribution of stresses in a splice bar of unsymmetrical cross sectional area and adapted to fit a standard rail.

A further object is to provide a splice bar of unsymmetrical cross section in which the stresses in the extreme vertical and horizontal fibres are balanced and in which the minimum amount of metal is used, thereby to obtain a splice bar of maximum efficiency and hence greatest economy.

A further object is to provide an improved splice bar, as above specified, which does not extend beyond the base of the rail with which it is adapted to be used.

Other objects will appear from the following description, reference being had to the accompanying drawings, in which

Figure 1 is a perspective view of the end portions of two adjacent rails joined by splice bars of my invention;

Figure 2 is a vertical transverse section of a rail joint drawn to three-fourths scale; and

Figure 3 is a similar section, full size, of the rail joint of my invention.

Splice bars, as used in rail joints, may be considered to be subjected to the stresses of a beam supported at both ends, for vertical loads and also for transverse horizontal loads.

It is a well recognized principle of design of beam sections that for maximum efficiency the stresses in the extreme fibres must be equal, which condition prevails in I-beams. Of course, an I-beam section cannot be used as a splice bar since the bar must conform to certain specifications of shape so as to fit between the rail head and base. Clearance must also be left for the flange of the car wheel so that the splice bar is necessarily unsymmetrical in shape. My present invention provides a section for splice bars which has some of the properties of the efficient I-beam section but which, at the same time, fills all the requirements of shape necessary or desirable in a splice bar.

In Figure 1 I have shown the ends of a pair of adjacent rails 4, 6, joined by splice bars 8 and 10 by suitable bolts 12, in the customary manner. In Figure 2 I have shown the transverse section through the rail joint in which the shape of the section of the splice bars 8 and 10 is clearly illustrated and showing the surfaces of the bars which lie in contact with the rail. The rail joint is held in place upon the ties by the usual spikes 14 and the splice bars are drawn into firm wedging engagement between the head 16 and the base 18 of the rail by nuts 20 threaded on the bolts 12, a lock washer 22 being interposed between each of the nuts 20 and the splice bar 10.

The rail illustrated is known as the 110-pound R. E. (American Railway Engineering Association).

As best illustrated in Figure 3, the splice bar section of my invention has a novel shape, the characteristics of which may best be described by the mathematical formulæ which govern the conclusions that the present shape is the most economical and efficient. In using these formulæ the following letters will be used and may be defined as follows:

	X—X'	Horizontal neutral axis of the section
	Y—Y'	Vertical neutral axis of the section
	C	Center of gravity (intersection of neutral axes)
5	<i>x</i>	Distance from vertical neutral axis to outermost fibre of right-hand portion of the section
	<i>x'</i>	Distance from vertical neutral axis to outermost fibre of left-hand portion of the section
	<i>y</i>	Distance from the horizontal neutral axis to the outermost fibre of upper portion of the section
10	<i>y'</i>	Distance from the horizontal neutral axis to the outermost fibre of lower portion of the section
	A	Total area of section
	ΔA	Elemental area
15	<i>u</i>	Distance from the center of gravity of an elemental area to the horizontal neutral axis
	<i>v</i>	Distance from the center of gravity of an elemental area to the vertical neutral axis
	M	Static moment
	I _{xx}	Moment of inertia about horizontal neutral axis
20	I _{yy}	Moment of inertia about vertical neutral axis
	S _x , S _{x'}	Section modulus of right and left portions, respectively, about the vertical neutral axis
	S _y , S _{y'}	Section modulus of upper and lower portions of section with reference to the horizontal neutral axis

25 As far as feasible, the above letters have been applied as reference characters in Figure 3 of the drawings.

The static moment of an elementary area and the total area about the neutral axis may be represented by the formulæ:

$$M_{xx} = u\Delta A \text{ or, } M_{xx} = \lim_{\Delta A \pm 0} \sum u\Delta A = \int u dA$$

$$M_{yy} = v\Delta A \text{ or, } M_{yy} = \lim_{\Delta A \pm 0} \sum v\Delta A = \int v dA$$

and:

$$y = \frac{M_{xx}}{A}, \quad x = \frac{M_{yy}}{A}; \quad \text{or} \quad y = \frac{\int u dA}{A}, \quad x = \frac{\int v dA}{A}.$$

35 The moment of inertia of a section may be defined as the summation of the products of the elementary areas of a section by the squares of their distances from the center of gravity of the section, being expressed in inches to the fourth power, the formula being:

$$I_o = \lim_{\Delta A \pm 0} \sum u^2 \Delta A = \int u^2 dA$$

40 or:

$$I_{xx} = I_o - Ay^2$$

where the moment of the section is taken about an axis parallel to the X—X axis and 45 at a distance *y* therefrom.

50 The section modulus is the quotient of the moment of inertia divided by the distance from the neutral axis to the outermost fibre. In an unsymmetrical section there may be two section moduli, the least being the determining factor in finding the resisting moment. In the splice bar section of my invention the section modulus of the portion above the horizontal neutral axis is substantially 55 equal to the section modulus of the portion below said axis. In a similar manner the section moduli of the portion to the right and

left of the vertical neutral axis are substantially equal.

Thus:

$$\int x = \frac{I_{yy}}{y} = \int x' = \frac{I_{yy}}{y'}$$

$$\int y = \frac{I_{xx}}{x} = \int y' = \frac{I_{xx}}{x'}$$

70 When this condition prevails, the splice bar will be of the most economical shape, since the stresses in the upper and lower outermost fibres will be equal and the stresses in the outermost right and left fibres will also be substantially equal whenever the bar is subjected to strains of a beam.

75 Of course, these conditions are present in I-beams of usual section, but my invention lies particularly in the provision of a splice bar of unsymmetrical section which has the properties of such a standard I-beam and which is so shaped as to be adapted to contact with the rail beneath its head flange and upon the base flange over substantial areas.

80 The splice bar section disclosed in the drawings has these desirable properties in that the section moduli of the upper and lower portions are substantially equal and

the section moduli of the portions to the right and left of the vertical neutral axis are substantially equal. These properties may best be illustrated by the following tabulations of the properties of the section shown in the drawings: 5

Area of section is 5.194 inches²
 Distance y' is 2.2143 inches
 Distance y is 2.2159 inches
 Distance x is 1.1529 inches
 Distance x' is 1.1596 inches
 Moment of inertia about horizontal neutral axis, I_{xx} is 9.585 inches⁴
 Moment of inertia about vertical neutral axis, I_{yy} is 1.494 inches⁴
 Section modulus, S_x , is 1.29 inches³
 Section modulus, $S_{x'}$, is 1.288 inches³
 Section modulus, S_y , is 4.32 inches³
 Section modulus, $S_{y'}$, is 4.33 inches³

From the above data it will be seen that in the splice bar section of my invention the section moduli are nearly equal for corresponding coordinates and that the differences are so small, when compared to production tolerances, as to be negligible. The above dimensions and properties are, of course, merely illustrative and will be different for splice bars designed for use with rails of different weight. 10

Within practical limits the above described splice bar section is the most economical possible for a given weight of material and for an unsymmetrical shape suited for engagement with the side of a rail. It will be noted that the outer edge of the lower portion of the splice bar lies practically coincident with the plane passing through the edge of the rail base flange, thus making it possible to spike the splice bar to the ties. 20

While I have shown and disclosed a particular embodiment of my invention, it will be apparent to those skilled in the art that slight variations may be made without departure from the principles of my invention. I, therefore, desire the scope to be limited only by the claims which follow. 30

I claim:

1. An unsymmetrical splice bar having the portions above and below the horizontal neutral axis of substantially equal section modulus and the portions to the right and left of the vertical neutral axis of substantially equal section modulus. 35

2. An unsymmetrical splice bar in which, when the bar is subjected to a strain, the stresses in the extreme upper and lower fibres are substantially equal, and the stresses in

the extreme right and left hand fibres are also substantially equal. 45

3. An unsymmetrical splice bar having intersecting neutral axes, in which the section modulus on one side of each of said neutral axes is equal to the section modulus on the other side of each of said neutral axes, and which is adapted to lie wholly within vertical planes passing through the edges of the base of the rail. 50

4. A splice bar of unsymmetrical section and having substantial areas adapted to contact with the base flange and head of a rail, in which the section moduli of the portions of the section to the right and left of the vertical neutral axis are substantially equal, and which is adapted to lie within vertical planes passing through the edges of the base of the rail. 55

5. An unsymmetrical splice bar adapted to lie entirely within vertical planes projected to the edges of the base flange of a rail, in which the section moduli above and below the horizontal neutral axis are substantially equal and the section moduli to the left and right of the vertical neutral axis are substantially equal. 65

6. An unsymmetrical splice bar adapted to have substantial areas of contact with the base flange and head of a rail, in which the section moduli above and below the horizontal neutral axis are substantially equal and the section moduli to the right and left of the vertical neutral axis are substantially equal. 75

In witness whereof, I hereunto subscribe my name this 27th day of January, 1928.

CHARLES W. BREED.
